[57] CLAIM

The ornamental design for a combined weightlifting belt and pouch, as shown and described.

DESCRIPTION

FIG. 1 is a perspective view of a combined weightlifting belt and pouch, showing my new design;

FIG. 2 is a fragmentary perspective view of the pouch portion thereof;

FIG. 3 is a front elevational view thereof, shown in an alternate position;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear elevational view thereof;

FIG. 9 is an enlarged fragmentary perspective view thereof, with the flap in an open position and the zipper in a closed position; and,

FIG. 10 is an enlarged fragmentary perspective view thereof, with the flap and zipper in an open position.
